UNITED STATES PATENT OFFICE.

EUGÈNE SCHNEIDER, OF PARIS, FRANCE, ASSIGNOR TO SCHNEIDER & CIE., OF PARIS, FRANCE, A LIMITED JOINT-STOCK COMPANY OF FRANCE.

GUN-SUPPORTING PLATFORM.

1,340,415.

Specification of Letters Patent. Patented May 18, 1920.

Original application filed July 30, 1917, Serial No. 183,595. Divided and this application filed August 8, 1918. Serial No. 248,996.

To all whom it may concern:

Be it known that I, EUGÈNE SCHNEIDER, a citizen of the French Republic, and a resident of 42 Rue d'Anjou, Paris, France, have invented a new and useful Improvement in Gun-Supporting Platforms, which invention is fully set forth in the following specification.

The present invention relates to improvements in gun carriage supports adapted to be mounted on bogies or trucks and supported by depressing and elevating devices, and resides in providing gun supports of the above character with sub-platforms whereby the support and platform are capable of relative turning movement around a common axis. The construction is such that the sub-platform may turn relatively to the gun support when the latter is carried by the bogies, and when the sub-platform is lowered and rests on the ground the gun support is enabled to turn on the sub-platform.

The gun support may assume various forms such as that of a traversing-platform adapted to receive a gun carriage on which a gun is mounted on trunnions, the carriage being adapted to slide on a track during recoil and return to battery. Any suitable depressing and elevating means such as screw jacks may be used to support the gun supporting platform.

The sub-platform is connected in any suitable manner to the underside of the gun support, permitting relative rotation between the support and sub-platform. I preferably make this connection by providing a bracket flange on one of the parts for receiving a sliding flange portion on the companion part, and also connect the support and sub-platform by a pivot. To facilitate relative rotation of the support and sub-platform, antifriction bearings are provided such as rollers mounted on one of the parts bearing against the companion part, and to reduce the effects of shock the axes of these bearings are preferably yieldingly mounted. The sub-platform may be, and preferably is, provided with anchoring means such as spades which are adapted to enter the ground when the support and platform are lowered to the ground for firing.

In order that the invention may be more readily understood, reference is had to the

accompanying drawings which illustrate 55 one constructional form of the invention and are intended to assist the description of the invention but not to define the limits thereof.

In said drawings:—

Figure 1 is a side elevational view of a gun carriage platform embodying my improvements; and

Fig. 2 is a plan view thereof.

In the drawings, S designates a gun support or gun supporting platform of the traversing type on which is mounted a gun carriage T slideable thereon in recoil and return to battery, and carrying a gun provided with trunnions resting in bearings on 65 the carriage. The gun supporting platform S is also provided with two-part collars M connected by hinge pins m. In these collars, screw-jack bodies or frames are mounted, and are adapted to turn. F is the elevating 70 and depressing screw of the jack and bears on a bracket D' pivotally engaging the axle B of the bogie wheels. D^a is a collar on the bracket D' adapted to limit the side to side movement of the axle B in the bracket D'. 80

U is a sub-platform which is revolvably connected to the underside of the gun supporting platform S by peripheral flanges which work in brackets S' on the platform and by a pivot V located in the axis of 85 rotation. W are rollers mounted in bearings which support the gun platform. J is a rod up and down which the jack-screw F slides and prevents turning of the screw.

The device thus far described operates as 90 follows: Assume the gun supporting platform S elevated and in traveling position. The bogie wheels A rest on the ground and support on their axles by means of the jack-screws the entire weight of the gun supporting 95 structure. When the place for conducting firing operations is reached, the sub-platform is turned into the direction for aiming as indicated in position U', Fig. 2. The levers L are turned in proper direction to 100 depress screws F and lower the platforms until the sub-platform rests on the ground. Continued movement of lever L will now lift the bogies off the ground. The gun supporting platform is now rotated into firing position on the sub-platform and the gun is in position to be moved in its vertical 105 plane of firing. To restore the system to

its original traveling position, the bogies are lowered in contact with the ground and the operations above described are reversed.

The subject matter herein described and claimed was originally presented in my co-pending application Ser. No. 183,595 filed July 30, 1917, of which the present application is a division.

What is claimed is:—

- 10 In a traveling gun carriage support of the character described, a platform having a track adapted to receive a gun supporting carriage slideable on said track during recoil and return to battery, and a sub-platform

having a pivot connection with said upper platform and having peripheral supporting connections therewith comprising curved flange members having a common center in said pivot, the flanges at one end of the platform having a longer radius of curvature than at the opposite end.

In testimony whereof I have signed this specification.

EUGÈNE SCHNEIDER.
